Primary Examiner — Melanie H Tung*Assistant Examiner* — Lavone D Tabor(74) *Attorney, Agent, or Firm* — Snell & Witmer LLP**CLAIM**

We claim the ornamental design for a toothbrush, as shown and described.

DESCRIPTION

FIG. 1 is a bottom, front, left side perspective view of a toothbrush showing our new design;

FIG. 2 is a right side elevational view thereof; and,

FIG. 3 is a front plan view thereof.

The broken lines are included for the purpose of illustrating portions of the toothbrush that are environmental or illustrative and that form no part of the claimed design.
